(57) **CLAIM**

We claim the ornamental design for a storage case, as shown and described.

DESCRIPTION

FIG. 1 is a front perspective view of a storage case;

FIG. 2 is a top view thereof;

FIG. 3 is a front view thereof;

FIG. 4 is a right side elevation view with the left side being a mirror image thereof;

FIG. 5 is a rear view thereof; and,

FIG. 6 is a bottom view thereof.

The left side of the storage case is symmetrical with the right side elevation view as shown in FIG. 4.
